Inventor
C. L. Horack

UNITED STATES PATENT OFFICE.

CHARLES L. HORACK, OF BROOKLYN, NEW YORK.

CAR-COUPING.

SPECIFICATION forming part of Letters Patent No. 252,767, dated January 24, 1882.

Application filed October 14, 1881. (No model.)

To all whom it may concern:

Be it known that I, CHAS. L. HORACK, a citizen of the United States, residing at Brooklyn, in the county of Kings and State of New York, 5 have invented certain new and useful Improvements in Car-Couplings, of which the following is a specification.

My invention relates to a car-coupling using a link and pin made stationary by means of a 10 washer, as described in my Patent No. 154,950, dated September 15, 1874, and as covered by Claim 1 of said patent. In the specification and drawings forming part of said patent the draw-bar to which link, pin, and washer are attached is shown to be of the same general form and construction as draw-bars made of wrought-iron generally are—viz., with two horizontal bars containing the pin-holes and a face-plate connecting them.

20 The object of the present invention is to adapt the same combination of link, pin, and washer to a draw-head of the general construction and outlines now usually given to cast-iron draw-heads. The draw-head, (which is the forward part of the draw-bar and is used for coupling purposes,) when made of cast-iron, is almost universally constructed like a box, with a hole in the top and one in the bottom for receiving the coupling-pin, and the front end left open 25 for admitting the coupling-link. By making certain changes in this form I am enabled to place the stationary link, when it is not needed for coupling purposes, in such a position as not to interfere with a link from an opposite draw-head which is to effect the coupling, and I also prevent the forward end of said stationary link, after a coupling has been effected by means of 30 a link connected with the opposite draw-head, from sliding out of the draw-head, and from 35 thereby obstructing the mouth of the same.

In the accompanying drawings, which form part of this specification, similar letters refer to similar parts throughout the several views.

Figure 1 is a side elevation of the draw-head 45 with link, pin, and washer attached, showing their position before a coupling has been effected by means of a link connected with the opposite draw head. Fig. 2 shows a longitudinal section of a draw-head with link, pin, and 50 washer attached, the link L being in a position ready to enter the opposite draw-head. Fig. 3

is a front elevation of a draw-head, showing the stationary link in a position through which it has to pass in order to be placed in the position shown in Fig. 1. Fig. 4 is a front view of 55 a draw-head, showing the section of a link, L', which is temporarily connected with the same, having effected a coupling with an opposite draw-head. The stationary link L appears separated from L' by the washer W. Fig. 5 is a 60 ground plan of the draw-head, showing the stationary link in a position similar to that shown in Fig. 1.

At or near one of the lower corners of the mouth of the draw-head D an enlargement or 65 extension, Y, of the same is shown. In the upper part of the opposite side of the draw-head a longitudinal opening, O, is indicated. The same, however, does not extend to the face of the draw-head.

70 When it is proposed to elevate the stationary pin P in order to effect a coupling by means of a link already connected with the opposite draw-head, the stationary link L must first be passed through the position shown in Fig. 3 to 75 that shown in Figs. 1 and 5.

75 The clear width inside of the draw-head is made small enough, and the rear end of the opening O is kept sufficiently forward or toward the mouth of the draw-head to make it impossible to pass the stationary link L in any other way to the position shown in Fig. 1. After the rear end of the stationary link has thus been passed through the opening O it becomes possible to elevate its forward end and the stationary pin and the washer to the position shown 80 in Fig. 1.

85 As shown in Fig. 4, the lip Z, near the mouth of the draw-head and above the recess Y, prevents the stationary link L from sliding out of 90 the draw-head D through the same channel through which it was introduced, after once another link, L', has entered the draw-head and effected a coupling. The thickness of the link L' and of the washer W, even if the forward 95 end of the stationary link L should have a tendency to drop down, hold the same up sufficiently to prevent it from passing under said lip Z. After the stationary pin P has been elevated to admit a link connected with an opposite draw-head, it is best to place and keep 100 said link in a somewhat reclining position, as

the shock caused by the meeting of the two draw-heads will then throw said pin into a vertical position and will cause it to drop, and by passing through the link already attached to the opposite draw-head to effect a coupling. To be able to maintain the pin in this reclining position until the opposite link has entered the draw-head, I extend the upper pin-hole backward, as indicated by letter X in Fig. 5, making this extension somewhat narrower than the pin-hole proper, so as to fit the pin very closely and to produce sufficient friction to maintain said pin in its elevated position. There is, however, a tendency on the part of the forward end of the stationary link, which is nearest to the mouth of the draw-head, after the pin has been placed in the elevated and reclining position described above, to drop down and to carry down with it the washer W, and also the pin, or at least to assume such a position as to partly obstruct the mouth of the draw-head and to offer resistance to the link connected with the opposite draw-head, which is to effect the coupling. To guard against this the forward part of the under side of the opening O is cut sloping backward, and a recess, R, is made in the roof of the draw-head, as shown in Fig. 2. Thus that part of the stationary link which, after it has assumed the position shown in Fig. 1, is nearest to the mouth of the draw-head is allowed to assume an elevated position behind the lip V. (Shown in Fig. 2.)

In the bottom of the draw-head the upper part of the lower pin-hole is made to conform approximately to the lower side of the washer W, thereby allowing the latter, when the stationary link is to be used for coupling purposes, to drop into the recess so formed, as shown in Fig. 2, and to thereby allow the rear end of said link some additional play up and down.

The shoulder S (shown in Figs. 1, 2, and 5) is intended as a protection for the draw-head, preventing the same from being forced under the car-platform and from having the stationary link L, when hanging out sidewise, forced against the neck-yoke, as said shoulder S is so arranged that the same comes to rest against the body of the car when there is a tendency to force said draw-head backward.

While the drawings show a round pin, P, a flat one may be used instead, in which case it might be best to cut a notch on the rear side of the same, and near the lower end, and use it for holding the link in an elevated position, when required, by resting said notch against the rim of the upper pin-hole.

Any suitable material may be used in the construction of the draw-head, providing it is made of such a form as to have it perform the services described above and covered by the claims below. By modifying it slightly a wrought-iron draw-bar such as now in use on many railroads, or a draw-head of wrought and cast iron combined, could be made to answer the purpose.

As appears from Figs. 1 and 3, the draw-head, directly back of the opening containing the stationary link, when not required for coupling purposes, is made wider than the part of the draw-bar adjoining it, so that, even if the shoulder S should be omitted, said stationary link would not be brought in contact with the neck-yoke around the draw-bar, but would be protected by means of said rear projection. 75

I claim as my invention and wish to secure by Letters Patent—

1. The combination of the link L and pin P, secured to the draw-head D, said draw-head being constructed with the recess Y on its face and with the side opening, O, for the purpose of passing through the same the stationary link L, substantially as described. 80

2. The combination of a link, L, and pin P, secured to the draw-head D, said draw-head being provided with the side opening, O, for the purpose of passing through the same the end of the stationary link L, substantially as described. 85

3. The combination of the link L and pin P, secured to the draw-head D, said draw-head being constructed with the side opening, O, for receiving the stationary link L, and the lip Z for preventing it from sliding out of the draw-head after another link has been introduced, substantially as described. 95

4. The combination of the stationary link L, pin P, and washer W with the draw-head D, said draw-head being constructed with the side opening, O, for the purpose of passing through it the rear end of the stationary link, and with the lip V for protecting the washer and the forward end of the stationary link when in an elevated position. 100

5. The combination of a link, L, and pin P, secured to the draw-head D by means of the washer W, said draw-head being provided with the side opening, O, for the purpose of passing through the same the end of the stationary link L, substantially as described. 110

6. The combination of the link L and pin P, secured to the draw-head D by means of the washer W, said draw-head being constructed with the recess Y on its face, and with the side opening, O, for the purpose of passing through the same the stationary link L, substantially as described. 115

7. The combination of the link L and pin P, secured to the draw-head D by means of the washer W, said draw-head being constructed with the side opening, O, for receiving the stationary link, and the lip Z for preventing it from sliding out of the draw-head after another link has been introduced, substantially as described. 120

8. The combination of the link L and pin P, secured to the draw-head D by means of the washer W, said draw-head being constructed with the side opening, O, the lips V and Z, and the recess Y, all substantially as specified. 125

9. The combination of the link L, pin P, and washer W with the draw head D, the upper

part of the lower pin-hole in said draw-head being made to conform with the lower side of the washer W, substantially as described.

10. The combination of a stationary link, pin, and washer with a draw-head, the latter being provided with a side opening for receiving the stationary link when not required for coupling purposes, and constructed with a

shoulder or projection back of said opening, for the purpose of protecting the stationary link.
